(57) **CLAIM**

The ornamental design for a tire, as shown and described.

DESCRIPTION

FIG. 1 is a front-perspective view of a tire of our new design;
FIG. 2 is a front view of our new design, the top, and bottom
views being identical thereto, the rear view being identical
in configuration, but inverted; and,

FIG. 3 is a right-side view of our new design, the left-side
view being identical thereto.

1 Claim, 3 Drawing Sheets
